UNITED STATES PATENT OFFICE.

JAMES M. HODGES, OF MILLERSBURG, KENTUCKY.

TRAP NEST.

Application filed May 23, 1923. Serial No. 640,993.

To all whom it may concern:

Be it known that I, JAMES M. HODGES, a citizen of the United States, residing at Millersburg, in the county of Bourbon and 5 State of Kentucky, have invented certain new and useful Improvements in a Trap Nest, of which the following is a specification.

The present invention relates to a nest 10 for chickens and the like and has for its principal object to provide a closure mechanism operatable by the nest. Said closure mechanism is normally disposed in an open position and is actuated to a closed position 15 by the weight of the fowl when in the nest.

Another object of the invention is to provide a nest of this nature having a simple 20 and efficient structure, one which is reliable in operation, inexpensive to manufacture, durable, sanitary, attractive in appearance, and well adapted to the purpose for which it is designed.

With the above and numerous other objects in view as will appear as the description progresses, the invention resides in certain 25 novel features of construction, and in the combination and arrangement of parts as will be hereinafter more fully described and claimed.

30 In the drawing

Figure 1 is a front elevation of the nest, Figure 2 is a longitudinal vertical section therethrough,

Figure 3 is a longitudinal horizontal 35 section therethrough.

Figure 4 is a detail perspective of the closure,

Figure 5 is a detail perspective of the weight for the closure, and

Figure 6 is a detail perspective of a platform used in the device.

Referring to the drawing in detail it will be seen that numeral 1 indicates the casing which is provided with an open end 2 partially closed at its bottom by a wall 3 having an outwardly projecting ledge 4 formed at its upper end. A closure 5 is provided adjacent one end with a pair of spaced ears 6 apertured to receive a bar 7 extending transversely of the opening 2 adjacent the ledge 4 whereby the closure is pivotally mounted. A pair of stop lugs 8 abut the closure as the same is in a closed position it being noted that the closure when in this 55 closed position is slightly inclined forward-

ly as is seen in Figure 2 and normally has a tendency to move to a horizontal position. This tendency to move to a horizontal position is aided by a weight 9 which is horseshoe shaped and disposed over the 60 outer edge of the closure 5. The intermediate portion of the closure 5 is formed of foraminous material as at 10. A platform 11 is mounted in the casing 1 adjacent the bar 7 and a little above the ledge 4. Thus 65 when the closure 5 is in an open position it will rest upon the ledge 4 and its inner end will abut the under face of the platform 11.

A nest 13 of any suitable structure is provided with a forward extension 14 to which 70 is attached a plurality of chains 15. These chains 15 are also attached to the slotted lugs 16 on the inner end of the closure 5. The rear end of the nest is supported by springs 17 which are attached by means of 75 hooks 18 to the rear end of the nest 13 and to lugs 19 projecting from the rear wall of the casing 1. This rear wall is provided with a plurality of apertures 20 for ventilation purposes. 80

When the closure 5 is in its normal open position the fowl walks over the same onto the platform 11 and jumps into the nest 13. The weight of the fowl when in the nest 13 causes the closure 5 to move to a 85 closed position in abutment with the stop lugs 8. The foraminous material 10 affords sufficient ventilation and light for the fowl and when it desires to leave the nest it will jump upon the platform 11 naturally 90 going toward the light coming through the foraminous material 10. When on the platform 11 the closure 5 will move to its open position resting on the ledge 4 and abutting the under surface of the platform 11. 95

A feed box 25 is mounted on one side of the casing and communicates with a trough 26 disposed adjacent the nest 13. A water tank 27 is disposed on the other side of the casing and communicates with a trough 28 100 adjacent and above the nest 13.

It is evident that these nests are possible to be arranged alongside of each other or one on top of another. These nests will prevent setting hens and the like from being disturbed and are so constructed that they may be easily cleaned since all parts thereof are readily accessible. 105

I have, in the present instance, shown and described the preferred embodiment of the 110

invention which will give in practice satisfactory and reliable results, and it is to be understood that the same is susceptible of modification in various particulars without departing from the spirit or scope of the invention or sacrificing any of its advantages.

Having thus described my invention what I claim as new is:—

- 10 1. In a device of the class described, a casing having an opening at one end, a ledge extending outwardly from the bottom of the opening, a platform disposed within the casing a distance from the opening and a little above the bottom end of the opening, a closure pivoted intermediate its ends adjacent the bottom edge of the opening so as to rest on the ledge and abut the under surface of the platform when open, a nest mounted in the casing, springs supporting 40 the inner end of the nest, an extension on the other end of the nest, slotted lugs on the inner ends of the closure, chains slidably engaged with the slotted lugs and attached to the extension said springs being tensioned 45 when said closure is in its closed position by drawing the nest toward the open end of the casing.

position the chains draw the nest toward the open end tensioning the springs.

2. In a device of the class described, a 30 casing having an opening at one end, a ledge extending outwardly from the bottom of the opening, a platform disposed within the casing a distance from the opening and a little above the bottom end of the opening, a 35 closure pivoted intermediate its ends adjacent the bottom edge of the opening so as to rest on the ledge and abut the under surface of the platform when open, a nest mounted in the casing, springs supporting 40 the inner end of the nest, an extension on the other end of the nest, slotted lugs on the inner ends of the closure, chains slidably engaged with the slotted lugs and attached to the extension said springs being tensioned 45 when said closure is in its closed position by drawing the nest toward the open end of the casing.

In testimony whereof I affix my signature in presence of two witnesses.

JAMES M. HODGES.
